UNITED STATES PATENT OFFICE.

GEORGE HOOD TABER, OF BINGHAMTON, NEW YORK.

SPARK-GAP-CONTROLLING DEVICE.

1,837,853.

Specification of Letters Patent. Patented Apr. 20, 1920.

Application filed March 8, 1919. Serial No. 221,402.

To all whom it may concern:

Be it known that I, GEORGE H. TABER, a citizen of the United States, and a resident of Binghamton, in the county of Broome and State of New York, have invented a new and Improved Spark-Gap-Controlling Device, of which the following is a full, clear, and exact description.

This invention relates to sparking devices for internal combustion engines or the like and has particular reference to means for varying the intensity of the spark by positive means under the control of the operator.

In the operation of internal combustion engines for automobiles or like machinery it is well known that when a spark from a battery or magneto is relied upon to initiate the action of the engine it is frequently desired or necessary to intensify the spark to overcome oily, sooty, or unfavorable conditions of the spark plugs. Accordingly it is desired to provide some means for increasing the gap either at the spark plug or at some other point in the circuit in order to effect the desired intensification of the spark. It follows, therefore, that the primary object aimed at in this construction is to provide a means whereby the gaps in all or any number of spark circuits may be increased or diminished at will and so maintained by positive means either during the starting of the engine or the subsequent operation thereof.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a front elevation of a fragment of a support such as a dashboard of a vehicle to which my improved mechanism is attached; and

Fig. 2 is a vertical section on the line 2—2 of Fig. 1 and indicating a view of my improved attachment.

Referring now more specifically to the drawings I show at 10 a spark coil shown as attached to the rear face of a dashboard 11 or other relatively stationary support,

and through which a series of terminals 12 project to which contact plates 13 are associated on the front of the dashboard.

14 and 15 indicate two horizontal bars of wood or other insulating material hinged together at 16. The upper bar 14 is held in rigid position and preferably spaced forward from the dashboard 11 by means of end brackets 17 in addition to the contact plates 13 which are preferably secured rigidly as by screws or the like to the front face of the bar 14. By virtue of the hinges 16 the bar 15 may be carried in substantially the same plane as the bar 14 but is adapted to be swung out of said plane as for example as shown in dotted lines in Fig. 2 or toward the dashboard. Any suitable means may be provided to variably control the position of the bar 15, but to this end I show an arm or lever 18 secured rigidly to one end of the bar 15 and to the lower end of the arm 18 I pivotally connect a plunger 19 extending loosely through a hole 20 formed in the dashboard preferably below the level of the spark coil 10 and the bars 14 and 15. The plunger is provided with a series of notches 21 shown as three in number and adapted to cooperate in succession with a fixed keeper 22 secured at one side of the plunger as indicated in Fig. 2 below the plunger. A spring 23 carried by the front face of the dashboard tends normally to draw the plunger downward or toward the keeper 22 so as to hold the keeper in engagement with whichever notch is selected by the operator. The hole 20 is large enough to provide for the lifting of the plunger free from the keeper for longitudinal adjustment thereof through the hole 20 and thereby determining the angular adjustment of the bar 15 with respect to the fixed bar 14. The spring 23 being hooked over the plunger does not interfere with the longitudinal adjustment of the plunger, but is always functional to hold the plungers in adjusted position when released.

At 24 I show a series of contact plates secured as by means of screws 25, or their equivalent, to the front face of the bar 25. The upper ends of the plates 24 are preferably bowed but may be slightly resilient, and the lower ends of the plates 24 constitute extensions to which connectors 26 of the high tension wires 27 are connected as by means of riding screws 28. The wires 110

27 will be understood as leading to the several spark plugs of the engine cylinders, and being flexible will not interfere with the angular adjustment of the bar 15.

5 With a device constructed and arranged as illustrated or in a manner substantially the same and with the plates 24 so shaped that in the normal position of the device as shown in full lines in Fig. 2, the upper ends 10 or points of the plates 24 will bear upon the plates 13 thereby making metallic connection between the terminals 12 and the high tension wires 27. In this position the plunger 19 is forward. In the starting of 15 a motor from a magneto, which requires considerable speed before a spark is generated, it is desirable to close the gaps between the contacts 13 and 24 as shown in full lines in Fig. 2, but after the motor is started and 20 it develops a skip due to oily or sooty spark plugs or otherwise, then the gaps between said contacts 13 and 24 are opened as far as desirable to increase the strength of the 25 sparks at such points and thereby the proper action of all of the spark plugs will be assured. Ordinarily, therefore, the gaps are closed at my device while the engine is being cranked.

This device is relatively simple in construction, cheap to install and maintain, and 30 is thoroughly reliable and efficient in practice.

I claim:

In a spark gap controlling device, the combination with an internal engine, of a 35 pair of relatively fixed and movable bars of insulation hinged together, a plurality of contact members associated with a fixed bar, a like number of movable contact members secured to the movable bar and coöperating 40 respectively with the fixed contact members, said fixed and movable contact members interposed in the ignition circuit of the engine between the spark plugs and the source of electrical energy, a lever fixed to 45 said movable bar to rotate it with respect to the fixed bar, thereby increasing or decreasing the spark gap between the fixed and movable contact, a manually operated connecting link pivoted to the lever, a plurality of notches in said link, a catch arranged to engage said notches, and a spring 50 normally holding the link in contact with the catch.

GEORGE HOOD TABER.
